(57) **CLAIM**

The ornamental design for the rotatable shelf assembly, as shown and described.

DESCRIPTION

FIG. 1 is a perspective view of a rotatable shelf assembly of the present invention;

FIG. 2 is a top plan view of the rotatable shelf assembly of FIG. 1;

FIG. 3 is a side elevation view of the rotatable shelf assembly of FIG. 1;

FIG. 4 is a bottom plan view of the rotatable shelf assembly of FIG. 1;

FIG. 5 is a perspective view of another embodiment of the rotatable shelf assembly of the present invention;

FIG. 6 is a top plan view of the rotatable shelf assembly of FIG. 5;

FIG. 7 is a front elevation view of the rotatable shelf assembly of FIG. 5; and,

FIG. 8 is a bottom plan view of the rotatable shelf assembly of FIG. 5.
